UNITED STATES PATENT OFFICE.

CHARLES H. MADSEN, OF TROY, NEW YORK.

STEP-CUTTING DEVICE.

1,419,875.

Specification of Letters Patent. Patented June 13, 1922.

Application filed October 20, 1919. Serial No. 332,087.

(FILED UNDER THE ACT OF MARCH 3, 1883, 22 STAT. L., 625.)

To all whom it may concern:

Be it known that I, CHARLES H. MADSEN, a citizen of the United States, and a resident of Troy, in the county of Rensselaer and 5 State of New York, have invented an Improvement in Step-Cutting Devices, of which the following is a specification.

The invention described herein may be used by the Government, or any of its officers 10 or employees in prosecution of work for the Government, or by any other person in the United States, without payment of any royalty thereon.

One object of this invention is to simplify 15 the customary constructions of step-cutting devices for cutting step threads on breech blocks and in breech ends of guns.

Another object is to provide a practically 20 non-chattering and substantially shockless device of this nature, which is a marked improvement over the customary constructions, which are characterized by shock and chatter in the operation thereof.

Another object is to provide a device, of 25 the character indicated, which is positive, reliable and efficient in operation.

With these objects in view, the invention resides, generally stated, in a cam-controlled cutting-tool holder maintained in constant 0 contact with the cam by a spring, tensioned by a revolving eccentric on the same shaft as the revolving cam, the throw of the eccentric and cam being on the same side, insuring an equal tension on the spring at the 35 different steps in the revolution of the cam.

The invention resides, further, in mounting the cam in a stationary housing, as distinguished from well known constructions, in which the whole housing is operated 40 by a large cam, resulting in shock and chatter, which leaves the work in a condition necessitating considerable fitting and filing.

The accompanying drawings disclose an 45 exemplary form of embodiment of the underlying principles of the invention, and like reference characters identify corresponding parts throughout the several views. Briefly described:—

50 Figure 1 is a top plan view, partly in section, of my step-threading device, shown in operative position in relation to the work;

Figure 2 is a view in side elevation thereof;

Figure 3 is an end view thereof, looking 55 at the end carrying the gear train; and

Figure 4 is a section on the line 4, 4, Figure 1.

Referring, now, in detail to the drawings:—

1 designates a housing suitably mounted and fastened on the cross slide of a lathe, and carrying a lateral extension 2.

Laterally carried by the extension 2 is a casing 3, which is hollow to provide a chamber 4 for the reception of a slideable tool-holder 5, a cam 6, and an eccentric 7.

The cam and the eccentric are mounted on a rotatable shaft 8 extending transversely through the casing and longitudinally 70 through the extension 2 and provided, at one end thereof, with a gear 9, which is one gear of a train comprising gears 9, 10, 11 and 12, the latter being carried by a rotatable shaft 13 revolvable from a suitable source of power. 75

The invention comprehends suitable means for maintaining the tool-holder 5 in constant contact with the cam 6. The drawing discloses a very simple and efficient form of such means. The exemplary form shown 80 comprises the eccentric 7, encircled by an eccentric strap 14 carrying ears 15, 15 between which is disposed, on a transverse pin 17 carried by said ears, the upper end of a rod 16. The rod passes through the upper 85 portion of the tool-holder 5 and into a recess 18 therein. Encircling the rod 16 is a coiled spring 19 bearing, at one end thereof, against the end wall of said recess 18 and, at its other end, against a collar or nut 19 carried 90 by the free end of said rod.

The cam 6 and eccentric 7 are, as shown in the drawing, disposed on the shaft 8 with the throw thereof on the same side, which insures an equal tension on the spring 19 at 95 the successive steps in the revolution of the cam 6.

It will be noted that, by mounting the cam 6 in the housing 3 and providing the eccentric 7 and the spring 19 to hold the tool-holder 5 firmly against the cam at all times, I have reduced shock and chatter to a negligible quantity, which is a decided advance over the prior art, so far as I am cognizant thereof, in which the whole housing is operable by a large cam, the resulting chatter and shock leaving the work in a condition requiring fitting and filing.

The specific character of work being operated upon as shown in the drawing, is a breech bushing B, which is held on a chuck C by means of a threaded securing ring D 5 and threaded bolts E passing through said ring into said chuck.

The operation of the device is apparent from the above detailed description of the construction of the parts and their relative 10 disposition, but, briefly stated, it is as follows:—

When the lathe is set in motion, the cam 6 revolves, through the medium of the shaft 8 and the train of gears 9, 10, 11 and 12, 15 moving the tool-holder 5 with the tool A against the work B, the spring 19 holding the tool-holder firmly against the cam at all times. The fact that the eccentric is placed on the shaft 8 so its throw is on the same side 20 as the cam 6 insures an equal tension on the spring at the different steps of the cam.

Having described my invention, what I claim as new and desire to secure by Letters Patent, is:—

- 25 1. A step threading device comprising a hollow casing, a rotatable shaft projecting therethrough, a cam carried by said shaft and disposed interiorly of the casing, a reciprocable tool-holder projecting into said casing, and means for maintaining said tool-holder in constant contact with said cam.
- 30 2. A step threading device comprising a hollow casing, a rotatable shaft projecting therethrough, a cam carried by said shaft and disposed interiorly of the casing, a reciprocable tool-holder projecting into said casing, and means for yieldingly maintaining said tool-holder in constant contact with said cam.
- 35 40 3. A step threading device comprising a hollow casing, a rotatable shaft projecting therethrough, a cam carried by said shaft

and disposed interiorly of the casing, a reciprocable tool-holder projecting into said casing, and spring-actuated means for maintaining said tool-holder in constant contact 45 with said cam.

4. A step threading device comprising a hollow casing, a rotatable shaft projecting therethrough, a cam carried by said shaft 50 and disposed interiorly of the casing, a reciprocable tool-holder projecting into said casing, and means for maintaining said tool-holder in constant contact with said cam, comprising an eccentric carried by said shaft 55 and a spring operatively connected with said eccentric and said tool-holder.

5. A step threading device comprising a hollow casing, a rotatable shaft projecting therethrough, a cam carried by said shaft 60 and disposed interiorly of the casing, a reciprocable tool-holder projecting into said casing, and means for maintaining said tool-holder in constant contact with said cam, comprising an eccentric carried by said shaft 65 and a spring operatively connected with said eccentric and said tool-holder, said eccentric being disposed on said shaft with its throw on the same side as the cam.

6. A step threading device comprising a hollow casing, a rotatable shaft projecting therethrough, a cam carried by said shaft and disposed interiorly of the casing, a reciprocable tool-holder projecting into said 70 casing, and means for maintaining said tool holder in constant contact with said cam comprising an eccentric carried by said shaft, an eccentric strap around said eccentric, a rod carried by said strap and projecting into said tool-holder, and a coiled spring encircling said rod and disposed in 75 said tool-holder.

CHARLES H. MADSEN.
